UNITED STATES PATENT OFFICE.

FREDERICK E. WARNER, OF BRIDGEPORT, CONNECTICUT.

TUMBLING-BARREL.

1,073,945.

Specification of Letters Patent. Patented Sept. 23, 1913.

Application filed May 28, 1913. Serial No. 770,444.

To all whom it may concern:

Be it known that I, FREDERICK E. WARNER, a citizen of the United States, residing at Bridgeport, in the county of Fairfield and 5 State of Connecticut, have invented certain new and useful Improvements in Tumbling-Barrels, of which the following is a specification.

My present invention pertains to improvements in tumbling barrels, and more specifically to an improved means for heating the same.

The invention in its preferred form is illustrated in the annexed drawings, 15 wherein:

Figure 1 is a sectional elevation of the barrel and its mounting; Fig. 2 a sectional view of the barrel-head, taken on the line 2—2 of Fig. 1, illustrating the interior construction of the barrel-head; Fig. 3 a transverse sectional view, on an enlarged scale, on the line 3—3 of Fig. 1; Fig. 4 a longitudinal sectional view on the line 4—4 of Fig. 1, taken at right angles to the section of 25 said figure, and the barrel being rotated a quarter turn; Fig. 5 a sectional view on the line 5—5 of Fig. 1, also illustrative of the construction of the barrel-head; and Fig. 6 a side elevation of the steam pipe connections, illustrating their relation to the dumping or swinging axis of the barrel.

The main object of the present invention is to provide a superior means for heating the barrel; to so construct such means 35 that it will clear itself of condensed steam; and also to provide steam-connections which will allow the barrel to be tilted as may be desired, while the steam is still on, and this without the use of rubber hose or the 40 like.

The barrel and its support, and the rotative and tilting means therefor are for the purpose of illustration substantially the same as those shown and set forth in Letters Patent No. 978,524, granted to me under date 45 of December 13, 1910, though as will be apparent the invention may be applied to almost any form of barrel.

In the drawings, 1 denotes the fixed base 50 or standard in which is swiveled, upon suitable bearings or hubs, a frame 2, which latter forms the support for the barrel-sustaining and rotating shaft 3. Said shaft has secured to it a worm gear 4, to which motion is imparted through a worm gear (not

shown) carried upon a driving-shaft 5, which is concentric with the swivel bearing of the frame 2. Fast and loose pulleys 6 and 7 are mounted on shaft 5.

A sector-shaped rack 8 is carried by frame 60 2, and through pinion 9, gear 10, pinion 11 meshing with said gear, and crank 12 secured to the shaft which carries pinion 11, the frame 2 and the parts supported thereby may be rocked or tilted as desired. All this 65 mechanism is common to the patent aforesaid, to which reference is made for a more detailed description.

The barrel-body may be said to comprise an inner shell or lining 13, an exterior shell 70 or wall 14, an outer connecting and spacing ring 15, and a head 16, the lining 13 being secured to an upstanding collar 17 formed thereon.

The head is provided with a relatively 75 large hub 18, to which shaft 3 is keyed. Said head is hollow, forming a chamber 19, into which live steam passes, through a port 20, formed in hub 18, the head likewise having a discharge channel 21, communicating at 80 its inner end with a discharge port 22, also formed in the hub. A pipe coil 23 is placed between the shells 13 and 14 of the barrel and preferably in close contact with the inner wall or shell, the inner end of the coil 85 being in communication with chamber 19, while the outer end is connected by a pipe 24 with the exhaust channel 21. Asbestos or other suitable heat-insulating material 25 will be packed between the coil and the exterior shell 14 of the barrel.

Loosely mounted on shaft 3 and bearing closely against a packing washer 26 interposed between it and hub 18, is a collar 27, said collar being provided with two concentric grooves 28 and 29 in the face thereof. Groove 28 is in constant communication with port 20 and with a steam supply pipe 30, threaded in an opening formed in the collar which communicates with channel or groove 28, while groove 29 is in constant communication with an exhaust pipe 31. Said pipes 30 and 31 are extended to one or the other side of the frame 2 of the apparatus and are connected to the supply and exhaust mains 32 and 33, Fig. 6, by swivel joints 34 and 35, which joints are located in line with the axis about which the frame 2 is tilted. By preference spring-pressed pins 36 and 37 will be interposed between 110

the frame 2 and the collar 27, said pins urging the collar up to washer 26 and effecting a steam-tight joint between the parts. The washer will, of course, be provided with suitable openings registering with the channels 28 and 29 and the ports 20 and 22.

The operation of the apparatus is as follows: When it is desired to heat the barrel, steam is admitted into the main 32, passing thence through pipe 30 and into the channel 28. From said channel it passes through the port 20 into the main chamber 19 formed in the head of the barrel, thence into coil 23, entering the lower end thereof, as indicated by the arrows in Fig. 1, and passing through the various convolutions thereof toward the outer or discharge end of the barrel. It then passes through the pipe 24, into the discharge channel 21, through port 22 in the channel 29, thence through exhaust pipe 31 into the exhaust main 33. The action of the steam will drive any water of condensation before it and a constant circulation will be thus maintained throughout the coil and through the head of the barrel. The rotation of the barrel also serves to carry the water of condensation forwardly and if for any reason the coil should become clogged by the water on account, for instance, of lack of proper steam pressure, it may be readily cleared by merely tilting the barrel.

It will be further noted that the swivel connections between the pipes 30 and 31 and the mains 32 and 33 are in axial alinement with the shaft or bearings upon which the barrel is tilted, so that there is no necessity for the employment of rubber pipes, slip joints or the like, and consequently there is little or no wear upon the parts.

Again, there is no necessity for shutting off the steam while the barrel is being tilted and the rotation of the barrel does not affect the passage of the steam into and from the coil.

While the steam connections and parts have been described somewhat in detail, it is obvious that the structure may be modified without departing from the spirit of the invention, so long as the functions herein set forth are retained.

Having thus described my invention, what I claim is:

1. In a machine of the class described, the combination of a barrel; a heating conduit located around the outer surface of the inner wall thereof; a supporting shaft to which said barrel is connected; means for rotating said shaft and the barrel; means for tilting the shaft and the barrel carried thereby; steam passages connected to the conduit and terminating in line with the axis about which the shaft and the attached barrel are tilted; inlet and exhaust mains; and suitable connections between said mains and

the steam passages, said connections likewise standing in alinement with the axis about which the shaft and barrel are tilted.

2. In an apparatus of the character described, the combination of a barrel having a hollow wall; a steam coil located within said wall; a head secured to one end of the barrel; steam passages formed in said head and connected, respectively, to the opposite ends of the coil; a hub formed on the head and provided with ports communicating, respectively, with the passages in the head; a shaft secured to the head; means for rotating the shaft; means for tilting the shaft about a substantially horizontal axis; a collar mounted upon the shaft; steam passages formed in said collar and opening, respectively, into the ports in the hub; pipes extending from said passages to a point in axial alinement with the horizontal axis about which the barrel and shaft are tilted; and steam inlet and exhaust mains swiveled to said pipes, whereby the barrel may be rotated and steam constantly introduced into and withdrawn from the coil, and the barrel and shaft tilted while steam continues to pass to and through the coil.

3. In an apparatus of the character described, the combination of a barrel, the body of which comprises an inner and an outer wall; a steam coil surrounding the inner wall; an insulating packing interposed between the coil and the inner face of the outer wall; a hollow head provided with inlet and exhaust passages connected, respectively, to the opposite ends of the coil; a hub extending from the head and provided with ports connected, respectively, with the passages in the head; a shaft extending into the hub and secured thereto; means for rotating the shaft; means for tilting the shaft and the barrel about a substantially horizontal axis; a collar loosely mounted upon the shaft, said collar having concentric passages formed in that face adjacent the hub; a washer interposed between said hub and collar, the washer having ports corresponding to the ports in the hub and likewise opening into the concentric passages in the collar; inlet and exhaust pipes connected, respectively, to the passages in the collar; and swivel connections for said pipes leading to inlet and exhaust mains, said swivel connections being located in alinement with the axis about which the shaft and barrel are tilted.

4. In an apparatus of the character described, the combination of a barrel, the body of which comprises an inner and an outer wall; a steam coil surrounding the inner wall; an insulating packing interposed between the coil and the inner face of the outer wall; a hollow head provided with inlet and exhaust passages connected, respectively, to the opposite ends of the coil; a

- hub extending from the head and provided with ports connected, respectively, with the passages in the head; a shaft extending into the hub and secured thereto; means for 5 rotating the shaft; means for tilting the shaft and the barrel about a substantially horizontal axis; a collar loosely mounted upon the shaft, said collar having concentric passages formed in that face adjacent 10 the hub; a washer interposed between said hub and collar, the washer having ports corresponding to the ports in the hub and likewise opening into the concentric passages in the collar; means for urging said collar 15 toward the washer; inlet and exhaust pipes connected, respectively, to the passages in the collar; and swivel connections for said pipes leading to inlet and exhaust mains, said swivel connections being located in 20 alinement with the axis about which the shaft and barrel are tilted.
5. In a machine of the character specified, the combination of a rotatable and tilttable barrel, the wall of the body whereof is hol- 25 low; a heating coil located in said hollow wall; a steam conduit opening into the lower end of the coil; and an exhaust conduit connected to the opposite end of the coil.
- 30 6. In a machine of the character specified, the combination of a rotatable and tilttable barrel, the wall of the body whereof is hol-

low; a heating coil located in said hollow wall; a head having ports or passages formed therein and connected, respectively, 35 to the opposite ends of the coil; and means for feeding steam to one of said ports and conveying exhaust from the other.

7. In a machine of the class described, the combination of a barrel having spaced 40 inner and outer walls; a supporting shaft to which said barrel is connected; means for rotating said shaft and the barrel; means for tilting the shaft and the barrel carried thereby; a continuous pipe coil sur- 45 rounding the inner wall of the barrel; a stationary steam collar surrounding said shaft and having grooves concentric with the axis of said shaft which are always in steam tight communication with the respec- 50 tive open ends of said coil; steam supply and exhaust pipes opening into said grooves; inlet and exhaust mains; and swivel connections between said mains and pipes and in line with the axis about which 55 said tilting is effected.

In testimony whereof I have signed my name to this specification in the presence of two subscribing witnesses.
